SINGLE ELECTRIC CABLE

Application filed August 31, 1927, Serial No. 216,731, and in Italy June 3, 1927.

This invention provides improvements in single conductor electric cables intended to carry high-tension and very high-tension current, said cables being insulated with impregnated paper and enclosed in a leaden sheath.

It is known that for this type of cable, there is an optimum ratio between the diameter D , outside the sheathing paper wrapping, and 10 the diameter d of the conductor properly so-called. According to the gradient theory, this ratio is $D : d = 2.718$.

In calculating the sectional area requisite for the conveyance of energy of very high 15 tension, it is often found that the diameter of the conductor, corresponding to the sectional area found, is below $D/d = 2.718$, so that many manufacturers have endeavoured to increase the diameter, by various devices, 20 with a view to obtaining the optimum diameter. These devices consist, generally, in disposing the individual wires forming the conductor round a fibrous or metallic support, or a support of some other material less expensive than the copper constituting the conductor.

It is also known that one of the most serious difficulties encountered by manufacturers of cables for very high tensions is the 25 determination of the length of time necessary for the complete drying of the paper and the complete impregnation of the same by the insulating mixtures.

To be able to recognize with certainty 30 whether all the humidity in the paper has been extracted is extremely important because excessive prolongation of the operation may injure the physical properties of the paper, whereas imperfect drying would adversely affect the working efficiency of the cable.

The impregnation is usually effected after 35 the determination of the necessary time, the viscosity of the mixture, the temperature and pressure employed, and the thickness and permeability of the dielectric being known.

However, owing to the large number of 40 variable factors, it is impossible to limit the duration of the impregnation stage to the 50 time strictly necessary, and it often happens

that, although an ample time margin has been allowed over the calculated period for the operation, tests reveal places where the impregnation is defective—sometimes over very extensive zones, and always in proximity to the conductor, that is to say, where the effort of the dielectric is strongest. These zones represent dangerous spots destined to become overheated, and therefore burn when the cables are in use.

The improvements forming the subject of the present invention enable the aforesaid inconveniences to be eliminated, and consist substantially in that:—

(1) A wrapping of paper with a very high 65 degree of porosity is provided round the copper cable, constituting the conductor of the requisite sectional area.

(2) A thin strip of copper, brass or other good conductive material is wound spirally 70 on said conductor, so as to form a cylinder with a diameter d corresponding to the ratio $D/d = 2.718$, in which D denotes the outside diameter of the ordinary insulating wrapper generally used for high tension cables and 75 wound over said metallic spiral and special paper.

The conductor proper is therefore a cable of ordinary construction and suitably calculated sectional area. The thickness of the 80 layer of highly porous paper should be such as to comply with said ratio, the metal spiral strip being connected to the inner conductor at the junctions of the lengths of cable and at the terminals of same.

The turns of said metal spiral strip are arranged to lie quite close together but without being in contact, in order to fulfil the dual purpose of maintaining the requisite 85 flexibility of the cable and of enabling the impregnating mixture to penetrate completely as far as the inner conductor. Paper wrapping, which may consist of several layers, is applied over the metallic spiral by the usual methods, until the thickness necessary for the tension for which the cable is designed is attained. Finally, the ordinary leaden 90 sheathing is applied.

The functions of the layer of paper inter- 100

posed between the conductor and the metallic spiral are as follows:—

(1) During the drying stage, the paper enables the progress of the operation to be measured by electrical means and the extraction of moisture to be interrupted at the suitable moment, thereby achieving the dual purpose of not uselessly prolonging a very expensive operation and of not keeping the insulating material at a high temperature longer than necessary.

The electrical measurements which may be carried out are insulation measurements, or better still, determining the losses of the electric by a bridge method with telephonic frequencies.

The measurement affects the portion which is the most difficult to dry, namely the layer of paper interposed between the metallic spiral and the copper conductor. By following the drying process systematically, it is possible to determine the maximum resistance of the insulation, or the minimum dielectric losses, corresponding to perfect drying.

(2) In the impregnation stage it is possible to recognize when the impregnating mixture reaches the layer of porous paper interposed between the conductive spiral and the conductor proper, since a sudden change will be observed in the insulation resistance, owing to the high conductivity of the mixture at the impregnation temperature.

If, instead of the insulation resistance, the capacity between said two members is measured, a considerable increase in the capacity and the losses will be noted when the mixture reaches the layer of highly porous paper.

Since this latter is the last to be moistened by the mixture, the impregnation of the cable proceeding from the outside towards the interior, it is known with certainty that, when the porous paper layer between the metal spiral strip and the conductor is impregnated, the whole of the external insulating wrapper is completely saturated with the mixture.

In order to realize this condition, the mixture must be prevented from gaining entrance into the interstices of the copper cable at the ends of the cable. As already mentioned the very reliable determination of the exact length of the impregnation stage represents a considerable advantage from both the technical and the economic point of view.

(3) When the cable is in use, the layer of highly porous paper interposed between the metal spiral strip and the conductor is not exposed to any electrical stress, because, as already mentioned, the metallic spiral strip is in electrical connection with the conductor proper at the junctions of the lengths of cable and at the extreme terminals thereof, so that said layer is situated between two surfaces of equal potential on the same electrical level.

In carrying out the invention, the edges of the metallic strip constituting the spiral are

suitably bent over towards the interior of the cable, thereby obviating the risk of forming projections with a small radius of curvature in the direction of the insulating material proper. However, the thickness of said layer being so calculated as to produce a diameter d of the spiral, complying with the optimum ratio, it follows that the gradient on the surface of contact between the insulating layer and the metal forming the spiral is appreciably less than it would be on the surface of the conductor proper in the absence of the metallic screen represented by the spiral. Moreover, from research and experiments carried on in Italy and America, it appears that, when the surface of the conductive spiral is smooth and perfectly cylindrical, the stress at the point of maximum gradient is considerably less than it would be if the conductor were artificially thickened, because the surface comprising individual wires wound round a supporting core gives rise to a dielectric stress from 15 to 20% greater than that due to a cylindrical conductor with a smooth surface.

In addition, the layer of highly porous paper forms a kind of reservoir for the insulating mixture, partly balancing the expansions undergone when the cable is in use and preventing any tendency of the expansions to affect the shape of the leaden sheath with the resulting formation (during the re-cooling of the cable) of empty spaces caused by the mixture shrinking to its original volume.

By way of example, a cable according to the invention is illustrated on the accompanying drawing to which reference will now be made.

Fig. 1 represents a section at right angles to the axis of the cable, and Fig. 2 is an axial view, the various layers composing the wrapping of the conductor being shown successively detached;

Fig. 3 represents a cross section, and Fig. 4 a partial axial section showing a method of electrical junction between the conductor and the metallic spiral for the junction terminals; and

Fig. 5 is a view, partly in axial section and partly in elevation, showing a method of joining the conductor and spiral at the end terminals.

In Figs. 1 and 2, reference numeral 1 denotes the conductor, calculated so as to provide the requisite sectional area of copper to convey the energy. The diameter of the spiral covering or conductive metal strip 3 is calculated, on the other hand, so as to obtain the optimum ratio between the diameter a and the diameter D resulting from the insulating layer 4, namely the ratio heretofore mentioned, $D/d=2.718$.

A layer 2 of highly porous paper is interposed between the conductor 1 and the strip

3, and a leaden sheath 5 protects the outer insulating layer 4 against external agencies.

In Figs. 3 and 4, the adjacent conductor lengths 1:1 of the cable are provided at the extremities with terminals 6:6 which are simply rings of conductive material threaded on the conductors, the two ends of which are placed in contact. The metal spiral 3 covers the terminals and the ends of the conductors are shown, and a soldering alloy 8 is poured in through the gap left between the edges of the strip 3, by suitable means, to form a rigid body between the terminals 6:6 and an excellent contact between the conductors 1:1 and the spiral 3.

Fig. 5 represents an end terminal comprising a cylindrical sleeve 7 threaded on the completely bare end of the conductor, and flared at one end, namely the end that projects beyond the conductor. Soldering alloy 8 is poured into this flared portion and also into the spiral gap of the strip 3 surrounding the sleeve 7, to replace the layer of porous paper 2. Said sleeve 7 is provided with a threaded extension for the usual connections.

Obviously, the junction and end terminals may differ from those shown without departing from the scope of the invention.

What I claim is:

30 A single conductor electric cable for very high tension electric current comprising a metal core formed in sections, a highly porous paper wound on said core, a metal strip spirally wound on the said porous paper so that 35 the adjacent edges of the strip are in close proximity but out of contact, a ring of conductive material threaded on the terminal portion of each section of the core and electrically connecting the spiral strip and core, 40 a layer of insulating material on said strip, the ratio between the outer diameter of the second layer and the diameter of said spiral being equal to 2.718 and a soldering alloy surrounding the core sections between the conducting rings forming a contact between the spiral and core sections.

In testimony that I claim the foregoing as my invention, I have signed my name.

ERNESTO FERRO.
